UNITED STATES PATENT OFFICE.

CHRISTIAN PETERSEN, OF PORTLAND, MAINE.

COMBINATION FURNITURE.

Application filed December 31, 1927. Serial No. 243,951.

In furnishing a home, among the most essential articles in the equipment are chairs. A very convenient although less often used article is a step ladder. A high-chair is another requirement when very young persons are members of the household.

My invention relates to combination furniture, and its principal object is to provide in one unitary structure the elements necessary to transform the device, when the parts are properly arranged, into either one of three separate articles of utility,—a high chair, an adult's chair and a step-ladder.

A further object is to so construct and fabricate the parts that those required for either of the three purposes may be brought into functioning position without detaching any of the individual parts employed for the other purposes enumerated.

I have illustrated the preferred embodiment of my invention by the use of the accompanying drawings, in which,—

Fig. 1 is a side elevation of the device shown as an ordinary household chair, the elements used to convert the chair into other articles being stowed away or folded into inoperative positions;

Fig. 2 is a side elevation of the device showing the parts used for a high-chair extended, and also illustrating the parts which serve as the lowest step in the step-ladder in their operative position;

Fig. 3 is a plan view of the parts as they are positioned in Fig. 2;

Fig. 4 is a front view of the arrangement shown in Fig. 2;

Fig. 5 is a fragmentary elevation, partly in section, of parts connected with the high-chair combination, the section being taken on line 5—5, Fig. 3;

Fig. 6 is a view partly in section taken on line 6—6, Fig. 4, showing the pantograph frame partly extended and the lowest step in the step-ladder combination fully retracted and locked;

Fig. 7 is an inverted plan of the locking means provided to secure the high-chair table to the pantograph frames;

Fig. 8 is a sectional view taken on line 8—8, Fig. 2, and

Fig. 9 is a sectional elevation, partly in section taken on line 9—9, Fig. 4, showing the pantograph frame retracted or folded into inoperative position between the upper right extensions of the chair legs.

Similar reference characters are employed

to indicate like parts throughout all the different views of the drawings.

The elements comprising my invention are built around and operate in conjunction with the parts of an ordinary household chair, and, in combination with the latter and with each other, provide the individual articles of household furnishings hereinafter to be described.

1, 1, represent the back legs and upright extended portions thereof, 2, 2, the front legs and 3 the seat of the chair,—the latter being hinged at the rearward end. The usual bracing and tying means are shown in the rungs 4 and back-boards 5.

Suspended between the upper extended portions of the legs, 1, 1, is a double pantograph frame, each side consisting, when extended, of one long vertical front leg 6, a horizontal bar 7, and a vertical bar 8, together with a channel member 9 which completes the four-sided frame.

This member 9 has downwardly extending ears 9' through which the parts are jointedly connected at points 10 and 11. The pantograph frame, complete, swings on the dowel 12 and when folded or retracted into inoperative position snugly fits between the two uprights or leg extensions on the legs 1.

A board 13 extends from one to the other of the horizontal bars 7 and serves as the seat for the high-chair. On the upper end of each of the leg 1 extensions is a plate 14 having a slot 15 in which operates a trunnion 16 projecting inwardly from each of the table side arms 17. The slots in these plates have off-set portions at the top and bottom,—those at the top being on the back side and those at the bottom on the front side of the slots.

Mounted on the under side of the high-chair table 18 are spring-rods 19 adaptable of engagement with notches 20 in the upper ends of the legs 6 for the purpose of holding the table 18 from accidental displacement from the pantograph frames. To guide the rods 19 and control their outward movement there are provided slotted brackets 21, having slots 22 in which the rods operate,—one of these brackets being provided on each side of the table.

When the rods 19 spring into engagement with the notches 20, the table is forced forwardly so that the trunnions 16 are then located in the lower off-set portions of the slots 15, which thus effectively ties the table

to the frames and to the chair extensions 1 and prevents the lifting of the table by a child who may be seated in the high-chair.

The adult chair-seat 3 has holes 23 adapted to receive the trunnions 24 on the bottom of the legs 6, so that when the frames are extended they may be held firmly against horizontal movement on the seat.

Beneath the seat 3, which may be swung upwardly on the hinge pins 25, is a bottom-board 26, which, with the proper side and end members make a box, which provides a convenient storage chamber,—the seat 3 serving as the cover therefor.

Swinging from each inner side of the legs 2, at 27, 27, is a horizontal bar 28; also making connection with each of these bars, at 29, is a leg 30. A bar 31, disposed in parallel relation to the bars 28, makes connection with the rungs 32 and 33, and secured to the two bars 28 is a platform 34 which serves as the lowest step in the step-ladder combination.

As is the case with the high-chair frame, this step-ladder frame is collapsible, and the latter may be housed between the two legs 2, 2 of the chair. To secure the step-ladder frame in its folded position I provide trunnions 35 in the seat 3 which, when the frame is retracted, engage notches 36 in the ends of the bars 28,—the seat first being lifted until the frame is in place and then lowered, which effects the locating of the trunnions in the notches.

The pins 27 do not extend transversely from leg to leg of the chair but project inwardly only so far as to provide proper support for the ends of the bars 28. They are shortened to allow the bar 31 to be folded between the legs 2 without interference.

In arranging to place the high-chair combination in position, the legs 6 are brought upwardly, as seen in Fig. 6, and swung forwardly until they assume a substantially vertical position, then lowered so that the trunnions 24 engage the holes 23 in the seat 3. The high-chair table 18 is then swung over and locked in position on the frame. Should a child be seated in the high-chair the table may be lifted bodily until the trunnions 16 reach the upper, off-set portions of the slot 15 then swung over and dropped into locked position on the frame. In a converse manner of operation the table may be lifted and swung into inoperative position while the child is still seated on the high-chair.

The lowest step in the step-ladder combination is put in place by first raising the seat 3 which disengages the trunnions 35 from the bars 28 and swinging the frame outwardly until the legs 30 reach the floor. With the device arranged as a step-ladder the seat 13 is moved into extended position

but the high-chair table 18 is left suspended on the back side of the chair.

It is obvious that other useful application might be made of the device,—as for instance, a chair for a boot-blacker,—the receptacle under the seat 3 being useful to store his implements and material when not in use.

The manner of constructing the parts, the simple operations required to put either of the combinations into effect and the completeness with which the attachments to convert the device into these combinations may be housed and condensed, makes it a very convenient and serviceable article of household use.

Having thus described my invention, what I claim and desire to secure by Letters Patent is:—

1. In a device of the character described, comprising in combination a chair, a rearwardly hinged seat on said chair, upright extensions on the rearward end of said chair, a plate on the upper end of each of said upright extensions having therein a relatively long, vertical slot provided with a rearwardly disposed off-set portion at its upper end and a forwardly disposed off-set portion at its lower end, a table, arms extending from said table and embracing said plates, a trunnion in each of said arms adapted to engage the slot in its adjacent plate, a pantograph frame oscillatively hung to each of said upright extensions, a seat secured to and extending from one to the other of the said pantograph frames, means to support the free ends of said pantograph frames on said hinged seat, and means to lock said table to said pantograph frames.

2. In a device of the character described, comprising in combination a chair, a rearwardly hinged seat on said chair, upright extensions on the rearward end of said chair, a plate on the upper end of each of said upright extensions having therein a relatively long, vertical slot provided with a rearwardly disposed off-set portion at its upper end and a forwardly disposed off-set portion at its lower end, a table, arms extending from said table and embracing said plates, a trunnion extending inwardly from each of said arms and adapted to engage the slot in the plate adjacent thereto, a pantograph frame oscillatively hung to each of said upright extensions, a seat connecting said pantograph frames, means to support the free ends of said pantograph frames on said hinged seat, means to hold said frames against horizontal movement while on and relative to said seat, and means to lock said table to said pantograph frames.

3. In a device of the character described, comprising in combination a chair having forward legs and rearward legs, an upright extension on each of said rearward legs,

- a hinged seat on said chair, trunnions depending from said hinged seat, a collapsible frame oscillatively connected to each of said upright extensions, a depending leg on 5 the free end of each of said collapsible frames, means to support the said depending legs on said hinged seat whereby when said frames are extended, said legs may be held against transverse movement on and relative 10 to said hinged seat, a fixed seat on and connecting the two lower members of said collapsible frames, a bar jointedly connected to and disposed on the inner sides of each of said forward legs of said chair, a platform 15 connecting said bars, a leg jointedly connected to the free end of each of said bars and adapted to support said platform in a horizontal position, and means on the outer ends of said bars to engage the said trunnions on said hinged seat whereby said platform and the parts immediately connected therewith may be held, when in retracted position, within the space between the two forward legs of said chair.
- 20 4. In a device of the character described, comprising in combination a chair having forward legs and rearward legs with vertical extensions thereof, a rearwardly hinged seat on said chair having two apertures in the top side thereof, trunnions depending from the under side near the forward end of said hinged seat, a double pantograph frame oscillatively connected at its lower inner corners to the said vertical extensions, a seat 25 on said double pantograph frame, depending portions on the outer end members of said pantograph frame, a trunnion on each depending portion of said pantograph frame adapted to engage one of the respective 30 apertures in said hinged seat, a bar oscillatively connected to and extending forwardly from each of said forward legs of said chair, a platform connecting said bars, a leg jointedly connected to each of said bars and extending to the floor and adapted 35 to support said platform in a horizontal position, and cut-away portions on the outer ends of said bars adapted to engage said trunnions in said hinged seat and hold said platform, when raised to its inoperative position, locked between the two said forward legs of said chair.
- 40 5. In a device of the character described, comprising in combination a chair, two forward legs, two rearward legs having upright extensions thereon, a plate at the upper end of each of said upright extensions having therein a vertically disposed slot with off-set portions on its upper rearward and lower forward sides, two pantograph frames oscillatively connected to and disposed between the said upright extensions, depending portions on the forward ends of said frames, a trunnion on the bottom end of each of said depending portions, a seat connecting said pantograph frames, a table, side bars extending from said table and embracing said plates, a trunnion on the inner side of each of said side bars adapted to engage one of the respective slots in said plates, means co-acting to secure said table to said pantograph frames simultaneously with the locking of said side bars to said upright extensions, with respect to vertical movement therebetween, a rearwardly hinged seat having apertures in the top thereof, trunnions projecting downwardly from said seat, a horizontal partition, having vertical sides secured thereto, disposed beneath and in spaced relation to said hinged seat, two horizontal bars oscillatively connected to and disposed between the forward legs of said chair, a depending leg jointedly connected to each of the said horizontal bars at their outer ends, a third bar disposed in spaced and parallel relation to the two said horizontal bars and adapted to hold said depending legs always in parallel relation to said forward legs of said chair, a platform connecting the two said horizontal bars, and means whereby said platform may be released for extension and locked in retracted position by raising and lowering, respectively, the said hinged seat.
- 45 In testimony whereof I affix my signature.
CHRISTIAN PETERSEN.
